CLAIM

We claim the ornamental design for a portion of a computer screen with a computer-generated image, as shown and described.

DESCRIPTION

A portion of the disclosure of this patent document contains material to which a claim of copyright protection is made. The copyright owner has no objection to the facsimile reproduction by anyone of the patent document or the patent disclosure, as it appears in the Patent and Trademark Office patent files or records, but reserves all other copyrights whatsoever.

The file of this patent contains at least one drawing/photograph executed in color. Copies of this patent with color drawing(s)/photograph(s) will be provided by the Office upon request and payment of the necessary fee.

The FIGURE is a front view of a portion of a computer screen with a computer-generated image.

The broken line drawing of a portion of a computer screen is for illustrative purposes only and forms no part of the claimed invention
